(57) **CLAIM**

The ornamental design for a child monitoring unit, as shown and described.

DESCRIPTION

FIG. 1 is a front perspective view of a child monitoring unit, showing my new design;

FIG. 2 is a front elevation view thereof;

FIG. 3 is a rear elevation view thereof;

FIG. 4 is a left side view thereof;

FIG. 5 is a right-side view thereof;

FIG. 6 is a top plan view thereof;

FIG. 7 is a bottom plan view thereof; and,

FIG. 8 is a front perspective view thereof in reduced form, shown in condition of use, and located outside of an article of clothing, such as a T-shirt.

The broken lines in FIG. 8 depicting a T-shirt illustrates environmental structure that forms no part of the claimed design.
